T. CAMPFIELD.
PORTABLE ELEVATOR.
APPLICATION FILED JUNE 22, 1914.

1,157,367.

Patented Oct. 19, 1915.

UNITED STATES PATENT OFFICE.

THOMAS CAMPFIELD, OF UNITY, ILLINOIS.

PORTABLE ELEVATOR.

1,157,367.

Specification of Letters Patent.

Patented Oct. 19, 1915.

Application filed June 22, 1914. Serial No. 846,636.

To all whom it may concern:

Be it known that I, THOMAS CAMPFIELD, a citizen of the United States, residing at Unity, in the county of Alexander, State of Illinois, have invented certain new and useful Improvements in Portable Elevators; and I do hereby declare the following to be a full, clear, and exact description of the invention, such as will enable others skilled in the art to which it appertains to make and use the same.

This invention relates to elevators, particularly to manually operated elevators for stores and similar places, and has for its object the provision of a novel elevator which may be moved from place to place for use and which is specially adapted for the elevating of cakes of ice from the floor to the ice receiving door of the type of large refrigerators used in stores, butcher shops, markets and other places.

An important object of the invention is the provision of an elevator of this character which is provided with means whereby it will be held firmly upon the floor while in use so that it cannot shake or be displaced while cakes of ice are being dragged onto or off from it.

A further object is the provision of a device of this character provided with roller carrying members whereby it may be readily dragged from place to place, the roller carrying members being capable of being swung so that the frame of the device will rest directly upon the floor to insure its remaining stationary.

Still another and more specific object is the provision of the device of this character having means engageable with the ceiling or a beam secured upon a refrigerator whereby the device may be additionally held against displacement.

An additional object is the provision of a device of this character which will be simple and efficient in operation, durable in service and a general improvement of the art.

With these and other objects and advantages in view, the invention consists in the novel construction, arrangement and combination of parts as will be hereinafter more fully described and claimed, and illustrated in the accompanying drawing, in which—

Figure 1 is a side elevation of my device in position ready for use, Fig. 2 is a similar view of the opposite side, Fig. 3 is a front

elevation, Fig. 4 is a cross sectional view on the line 4—4 of Fig. 1, Fig. 5 is a top plan view, Fig. 6 is a vertical sectional view through the lower portion of the device showing the roller carrying members swung so as to support the device upon the rollers, and Fig. 7 is a perspective view showing a modified means for holding the device stationary.

Referring more particularly to the drawing, the numeral 10 designates front uprights which are spaced from and parallel with similar rear uprights 11. The uprights 10 and 11 are connected and supported at their upper ends by cross bars 12 and 13 which are suitably braced as shown. The lower ends of the uprights are connected by cross bars 14 and 15. The uprights are further braced by diagonal arms 16.

An elevator member is disposed between the uprights and comprises an open rectangular frame comprising a top 17, a bottom 18 extending beyond the rear uprights 11, and corner posts 19 formed to engage the inner corners of the uprights. When the elevator member is in its lowermost position, the bottom 18 is disposed upon the cross bars 14 and 15 and alines with an inclined guide member 20 hinged upon the forward cross bar 15 as shown at 21.

In order that the elevator member may be raised and lowered, I provide a mandrel 22 journaled in brackets 23 secured upon the forward uprights 10 and provided upon its end with a gear 24. A cable 25 has one end secured to the mandrel 22 and extends upwardly and over a pair of rollers 26 journaled in bars 27 secured across the top cross bars 12, and has its other end secured to the top 17 of the elevator member as shown at 28. A shaft 29 is journaled on the bracket 23 and is provided upon one end with an operating handle 30 and has secured thereon a pinion 31 meshing with the gear 24. It will be seen that when the shaft 29 is rotated by the handle 30 the mandrel 22 will be turned and the elevator member raised within the frame formed by the uprights.

In order that the elevator member may be held at any desired position, I preferably provide means for locking the mandrel against rotation, which means may conveniently be a ratchet 32 secured upon the shaft 29 and engageable by a pivoted pawl 33 upon the adjacent upright 10.

In order that my device may be transported conveniently from place to place, I provide members 34 hinged, as at 35, upon the cross bars 14 at the bottom of the frame. 5 Rollers 36 are journaled adjacent the free edges of the members 34. When the device is in position to be moved from place to place, the members 34 are in the positions shown in Fig. 6, that is, the members 34 will 10 be disposed vertically beneath the cross bars 14.

When it is desired to adapt my device for use, so that the rollers 36 will not engage the floor, the members 34 are swung upwardly and outwardly as shown in Figs. 1, 15 2, 3, and 4 of the drawing. In order to accomplish this, I provide a rod 37 journaled through bearings 38 secured upon the cross bars 14. The rod 37 is provided at one end 20 with an operating lever 39 by which it may be rocked. Crank arms 40 are formed on the rod 37 and have their horizontal portions 41 extending through rings 42 pivotally secured upon the members 34. The device 25 being in the position shown in Fig. 6, with the rollers 36 engaging the floor, rocking the lever 39 to either side will cause the cranks 40 to move upwardly, thereby swinging the members 34 upwardly and allowing the lower ends of the uprights 10 30 and 11 to rest upon the floor.

The use of my device is as follows. After the device has been moved, as by dragging it upon its rollers to the ice box or other 35 place where it is needed, the members 34 are swung upwardly, as described, so that the device will rest with its uprights engaging the floor. The elevator member being in its lowest position, cakes of ice or the like 40 are slid up the guide member 20 and on to the bottom 18 of the elevator. Then by turning the handle 30, the cable 25 will be wound upon the mandrel 22 and the elevator member will be raised to the desired 45 position. The cakes of ice or the like may then be dragged from the bottom 18 of the elevator and into the refrigerator or other place where they are desired.

In order that the device may be held 50 rigidly in place and prevented from wabbling or shaking I provide a vertically extending bar 43 slidable within guides 44 secured upon cross bars 45 connecting two of the side uprights. The bar 43 may be slid 55 upwardly into a slot 46 formed in a member 47 adapted to be secured upon the ceiling of the room or building in which the device is used. A pin or bolt 48 may then be inserted within the proper one of a series of 60 apertures 49 formed in the bar 43 so that it will engage the top face of the lowermost guide 44 for preventing the rod 43 from slipping out of the slot 46. The bar 43 is prevented from slipping through the guide 65 44 by a lug 50.

If the refrigerator to be filled does not extend all the way to the ceiling of the room, I may secure a beam 51 on the refrigerator provided adjacent its end with a slot 52 for the reception of the rod 43, instead of using 7 the slotted member 47, as shown in Fig. 7.

After the device has been used, the guide plate 20 may be swung upwardly upon its 75 hinges 21 and secured between the uprights 10 by a turn button 51. The lever 39 is then rocked back to its original position, whereupon the members 34 will be swung back into their original positions under the cross bars 14 with the rollers 36 engaging the floor. The device may then be rolled to any desired place. 80

From the foregoing description and a study of the drawing it will be apparent that I have thus provided a novel and simple elevator device which may readily be rolled 85 from place to place and which may be held securely in position at any desired place of use.

It will be readily understood that I reserve the right to make various changes in the form, construction and arrangement of parts without departing from the spirit of the invention or limiting the scope of the subjoined claims.

Having thus described my invention, I 95 claim:

1. A device of the character described comprising a frame, an elevator member vertically movable within said frame, a windlass for moving said elevator member, and means for steadyng the device in its position, said means comprising a member secured on the ceiling above the device and provided with a slot and a bar held for vertical movement on said frame and engageable in said slot, and means extending through said bar and engaging a portion of said frame for preventing downward movement of said bar out of said slotted member. 110

2. A device of the character described comprising a frame, an elevator member vertically slidale therein, guide rollers on the frame, a cable secured to said elevator member and extending upwardly over said rollers, a manually operated mandrel for reeling said cable, guide brackets secured on said frame, a bar vertically slidale within said brackets, a lug on said bar adapted to engage one of said brackets for preventing 115 said bar from slipping through said brackets, said bar being provided with a plurality of openings, a slotted member adapted to be secured upon the ceiling above the device and adapted to receive the end of said bar, and a pin engaging a selected one of said openings and contacting with the top of one of said brackets for preventing 120 downward movement of said bar. 125

3. In a device of the character described 130

comprising a frame and a manually operated elevator member slidable therein, roller carrying members hinged upon the lower portion of said frame, and means for swinging said members whereby said rollers may be engaged with or disengaged from the floor, said means comprising a rod journaled for rocking movement on the lower portion of said frame, a hand lever formed on one end of said rod, a pair of crank arms formed

on said rod, and rings secured on said hinged members and engaged by said crank arms, whereby rocking of said rod will raise or lower said hinged members.

In testimony whereof, I affix my signature, in the presence of two witnesses.

THOMAS CAMPFIELD.

Witnesses:
